POPPET VALVE ASSEMBLY

Gordon L. Tescher, Anderson, Ind., assignor to
Tescher Corporation, Anderson, Ind.

Application December 18, 1950, Serial No. 201,275

2 Claims. (Cl. 251—125)

1

This invention relates to a new and improved poppet valve assembly designed primarily for use in a fuel pump for a two-cycle internal combustion engine, although not restricted to this field of use.

The principal object of the invention is to provide a novel valve assembly which will be free-floating and self-seating and will faultlessly function even at high-speed operation.

Another object is to provide a valve assembly which may be easily and inexpensively manufactured, and may be installed and replaced without difficulty.

A further object is to provide a valve assembly including a spring arm for yieldably holding the valve against its seat and a stop arm for limiting valve opening, and to unitarily connect said spring arm with said stop arm to facilitate initial assembly and to prevent possible loss of the spring arm when making repairs or replacements.

A still further object is to form the spring arm in a novel manner facilitating its connection with both the valve and the stop arm.

With the foregoing and other objects in view that will become apparent as the nature of the invention is better understood, the same consists in the novel form, combination and arrangement of parts hereinafter more fully described, shown in the accompanying drawing, and claimed.

In the drawing:

Fig. 1 is a top plan view of a fuel pump embodying two of the valve assemblies and locating them in dotted lines.

Fig. 2 is a top plan view of the central pump casing section and the outlet valve assembly therein.

Fig. 3 is a bottom plan view of the upper pump casing section and the inlet valve assembly therein.

Fig. 4 is a vertical sectional view on line 4—4 of Fig. 1, showing portions of both the inlet and outlet valve assemblies partly in transverse section and partly in elevation.

Fig. 5 is a vertical sectional view on line 5—5 of Fig. 1, showing the outlet valve assembly in longitudinal section.

Fig. 6 is a perspective view showing one of the valves and the associated spring arm and stop arm.

To facilitate explanation the construction disclosed in the drawing will be rather specifically described, but attention is invited to the possibility of making variations.

The fuel pump casing in which two of the improved valve assemblages have been disclosed, in-

cludes an upper section 10, a central section 11 and a lower section 12 all secured together by screws 13. The upper section 10 is formed in its lower side with two chambers 14 and 15, with an inlet 16 and vertical port 17 placing this inlet 16 in communication with the chamber 14, and with an outlet 18 leading from chamber 15. The central section 11 is provided, in its upper side, with one chamber 14' communicating with the chamber 14 and with a second chamber 15' communicating with the chamber 15. The lower side of this central section 11 is formed with a chamber 19. Ports 20 and 21 place this chamber in communication with the chambers 14' and 15', respectively. A diaphragm 22 closes the lower side of the chamber 19. The lower casing section 12 is provided with a chamber 23 closed at its upper side by the diaphragm 22, and with a passage 24 communicating with said chamber 23. A spring 25 acts downwardly on the diaphragm and reacts against the casing section 11. The passage 24 is to be connected with the crank case of a two-cycle internal combustion engine, whereby the plus and minus pressures in said crank case during engine operation will cooperate with the spring 25 to pulsate the diaphragm and produce the desired fuel pumping, with the aid of the valve assemblies hereinafter described in detail.

Two of the valve assemblies are employed—an inlet assembly 26 associated with the lower end of the port 17, and an outlet assembly 27 associated with the upper end of the port 21. The construction of the outlet assembly 27 is fully shown in the drawings and will be specifically described. The inlet assembly 26 is a duplicate of the outlet assembly 27 except that it is inverted. At least some of the reference numbers used in describing the assembly 27 will be found also on the assembly 26, plus the exponent "a," for identification, and this will obviate a separate description of said assembly 26.

The assembly 27 includes a valve body 28, a stop arm 29 for limiting the opening movement of said valve body 28, and a spring arm 30 for yieldably holding said valve body 28 against its seat. The body 28 is preferably of disk-like form with a flat lower surface to contact with a flat seat S on the casing section 11. The body 28 is provided with a central upstanding integral stud 31, and it is by preference formed from Bakelite or the like. The stop arm 29 is a plain strip of metal having its ends offset into different planes. One of these ends is formed with a central opening 32 for the reception of an attaching screw 33 which is driven into

the casing section 11, and the other end of said arm is in the upward path of the stud 31 as best seen in Fig. 5. The anchored end of the arm 29 is also formed with two smaller openings 34 laterally spaced from the opening 32. The spring arm 30 is formed from a single length of spring wire bent into V-shape and having a coil or eye 35 at its bight, the ends of the wire being passed upwardly through the openings 34 and clinched as shown at 36 in Figs. 2 and 6. The coil or eye 35 rather loosely receives the stud 31 of the valve body 28. There is thus provided an easily manufactured and installed assembly in which the spring arm 30 is unitarily attached to the stop arm 29, in which said stop arm may be bent to adjust the extent of valve opening, and in which said spring arm and stop arm are readily removable for replacing a worn valve body 28 with a new body, the construction also facilitating substitution of an entire new assembly if desired. Tightening of the screw 33 not only attaches the arm 29 rigidly to the casing section 11 but clamps the ends of the V-shaped wire arm 30 between said arm 29 and the underlying port of said casing section, and if the latter be of sufficiently soft material, said clamped ends will be embedded somewhat therein. The assembly will function with unusual effectiveness even at high speed operation and the valve is of floating and self-seating nature.

From the foregoing, it will be seen that novel and advantageous provision has been made for attaining the desired ends, and while there is herein shown and described the preferred embodiment of the invention, it is nevertheless to be understood that minor changes may be made

therein without departing from the spirit and scope of the invention as claimed.

I claim:

1. A valve assembly comprising a valve body to contact with a seat, said body having a central stud at the side thereof remote from its seat-engaging surface, a stop arm having one end disposed in the path of said stud to limit valve opening, the other end of said stop arm having an opening to receive an attaching fastener, said other end of said stop arm also having two laterally spaced relatively small openings, a spring arm comprising a V-shaped length of spring wire having an eye at its bight receiving said stud, the ends of said wire being extended through said relatively small openings and clinched to connect them with said stop arm, said spring arm exerting pressure on said valve body in valve closing direction.
2. A structure as specified in claim 1; the end portions of said spring wire being disposed for clamping against the above mentioned support upon tightening of the fastener passed through the first mentioned opening.
